UNITED STATES PATENT OFFICE.

JOHN T. DE MOSS, OF THORNTON, WEST VIRGINIA, ASSIGNOR OF ONE-HALF TO JOSEPH W. MARTIN, OF GRAFTON, WEST VIRGINIA.

LOCKING WHIP-SOCKET.

No. 927,501.

Specification of Letters Patent.

Patented July 13, 1909.

Application filed February 26, 1909. Serial No. 480,102.

To all whom it may concern:

Be it known that I, JOHN T. DE MOSS, a citizen of the United States, residing at Thornton, in the county of Taylor and State of West Virginia, have invented certain new and useful Improvements in Locking Whip-Sockets, of which the following is a specification.

This invention relates to whip sockets of that type which are intended to prevent the loss of whips either by the same being shaken out or stolen.

The invention consists in certain novel details of construction which will be herein-after described and claimed, and illustrated in the accompanying drawings, in which—

Figure 1 is a side elevation of a whip socket embodying the features of this invention and showing one form of operating devices therefor; Fig. 2 is a vertical sectional view of the socket shown in Fig. 1; Fig. 3 is a detail of a portion of the sleeve to be hereinafter described; Fig. 4 is a transverse section on the broken line 4—4 of Fig. 1; Fig. 5 is a view in elevation showing a modified application of the invention to a carriage body shown in section; Fig. 6 is a bottom view of the same, and Fig. 7 is a detail hereinafter described.

Throughout the following detail description and on the several figures of the drawings similar parts are referred to by like reference characters.

Referring particularly to the drawings the numeral 10 indicates a whip socket adapted to be connected to the dash board or other portion of a vehicle in a well known manner. The upper end of the socket is fitted with a flexible gasket 11 to prevent rattling. The bottom of the socket 10 is open and in said opening is movably mounted a sleeve 12 having an open upper end to receive the whip and whose lower end has secured therein a plug 13, indicating one means whereby the sleeve may be connected to an operating rod 14. The sleeve is provided on opposite sides and opposite each other with a plurality of slots 12' substantially midway of its upper and lower ends. A pair of spring catches 15 are secured upon the inner surface of the socket 10 in any suitable manner and having their lower ends projecting normally through the slots 12' and into the path of the head or rib 16 on the whip as indicated in dotted lines in Fig. 1, and also in Fig. 4 in full

lines. The socket 10 being stationary, when the sleeve 12 is drawn downwardly by any suitable means connected to the rod 14 the walls of the sleeve 12 at the upper ends of the slots will impinge against the springs 15 and cause them to be withdrawn out of the path of the said head 16, retracting the lower ends of the springs into the slots, as shown in full lines in Fig. 2. The whip at this time may be withdrawn from the socket in an ordinary manner.

As one means for operating the rod 14 and the sleeve connected thereto, there is shown in Fig. 1 a lever 17 pivoted at 18 to the vehicle body. The said lever and parts 70 connected thereto are normally held upward by means of a spring 19, whereby the catches 15 will always be in position to engage the whip. Upon depression of the lever 17 by the foot the sleeve will be drawn down to 75 the position indicated in Fig. 2.

A modification of the operating means for the sleeve is shown in Figs. 5 and 6. As herein shown the rod 14' projects downward through the bottom of the vehicle body 80 where it is connected to a lever 20 connected to a rock shaft 21 journaled in bearings on the bottom of the vehicle body. A spring 19' associated with the rock shaft 21 normally holds the rod 14' upward. The rock 85 shaft 21 is provided with a crank 22 having a plunger 23 connected thereto and extending upwardly through the bottom of the vehicle body. Upon depression of the plunger 23 the rock shaft will be operated 90 to cause downward movement of the rod 14' and the parts connected thereto. When it is desired to positively lock the device the plunger 23 may be provided with a slot 23' for the reception of a padlock 24. It will be 95 seen, therefore, that when thus locked it will be impossible for the device to be operated to release the whip.

The several parts of the device may be made of any suitable materials and relative 100 sizes and it is understood that the details of construction may be varied to a certain extent without departing from the scope of the invention hereinafter claimed.

Having thus described the invention, what 105 is claimed as new is:

1. In a locking whip socket, the combination of a stationary socket member, a sleeve 110 slideable therein and having a lateral slot, means connected with the sleeve to normally

hold the same elevated within the socket member, and means connected to the socket member and extending through said slot into the path of the whip head.

- 5 2. In a device of the character described, the combination of a stationary socket member, a sleeve slidably mounted within the socket member, and having a pair of slots, a pair of spring catches connected to the 10 inner wall of the socket member and projecting into said slots into the path of the whip head, and means for controlling the position of the sleeve and the spring catches.
3. In a device of the character described, 15 the combination of a socket member having an open lower end, a sleeve slidably mounted

in said open end of the socket member and having a rod connected to its lower end, said sleeve being provided with slots, a pair of spring catches connected to the inner face of 20 the socket member and coöperating with the wall of the sleeve at the upper ends of the slots, means to operate the rod and sleeve downwardly to cause the spring catches to be retracted from the sleeve, and means to 25 elevate the rod and sleeve.

In testimony whereof I affix my signature in presence of two witnesses.

JOHN T. DE MOSS.
